COIN CONTROLLED POSTAGE AFFIXING
DEVICE FOR LETTERS

David H. Brook, Brooklyn, N. Y.

Application July 13, 1934, Serial No. 734,902

4 Claims. (Cl. 194—78)

The object of the present invention is to provide a device for receiving a letter and affixing thereon a postage paid designation in accordance with the respective value or number of coins inserted into a slot or slots. The device may be mounted upon a governmental mail box or may be placed at suitable points, as, for example, drug and cigar stores. The device eliminates the necessity of purchasing adhesive stamps and applying them to the envelopes of letters preparatory to mailing.

The invention will be described with reference to the accompanying drawings, in which:—

Fig. 1 is a fragmentary perspective view of a governmental mail box having an embodiment of the invention applied thereto.

Fig. 2 is a side elevation of the device with the right-hand side plate removed immediately prior to release of the upper pawl for changing the feeding direction of the inking ribbon, certain parts being broken away.

Fig. 3 is a fragmentary side elevation similar to Fig. 2 showing the positions of the parts upon release of the upper pawl.

Fig. 4 is a transverse section on the line 4—4, Fig. 2, looking in the direction of the arrows.

Fig. 5 is a transverse section on the line 5—5, Fig. 3, looking in the direction of the arrows.

Fig. 6 is a horizontal section on the line 6—6,

Fig. 11.

Fig. 7 is a horizontal section on the line 7—7, Fig. 11.

Fig. 8 is a fragmentary vertical section on the line 8—8, Fig. 7.

Fig. 9 is a vertical section on the line 9—9, Fig. 8.

Fig. 10 is a sectional elevation on the line 10—10, Fig. 11.

Fig. 11 is a sectional elevation on the line 11—11, Fig. 10.

Fig. 12 is a detailed view in elevation of an inking ribbon feed ratchet wheel and its detent.

Referring to Fig. 1, a usual type of governmental mail box is indicated at 1, and at 2 is shown a casing and exterior operating members of an embodiment of the invention. At the top of the device 2 is a coin slot 3 for the insertion of coins for special delivery and air mail, or for multiple-ounce letters, as, for example, the insertion of one dime will emboss on the letter-envelope "three-ounce, first-class postage". Coin slot 4 is adapted to receive one-cent pieces and suitable multiples thereof, as, for example, three one-cent pieces. On the front wall of the device 5 is an operating handle 5 below which is a coin regulating thumb wheel 6 adapted to be moved to three positions for air mail and special delivery, also one-cent postage, two-cent and three-cent postage.

In the embodiment of the invention illustrated,

the embossing stamps are disposed rearwardly of an inking ribbon. The ribbon lies adjacent a passageway at the side and top of the device for reception of the letter, the passageway being indicated at 7. In the present embodiment, there are five embossing stamps indicated respectively at 8, 9, 10, 11 and 12. The embossing stamps are carried by a transverse frame plate 13 having horizontal apertures to receive endwise movable shafts, each shaft carrying one of the embossing stamps. The ends of the shafts project forwardly of frame member 13. The shaft 8x for embossing stamp 8 is of minimum extension. The shaft 9x of embossing stamp 9 projects forwardly of shaft 8x and the shaft 10x of embossing stamp 10 projects forwardly of shaft 9x. In this manner the embossing stamps may be successively operated by a single operating member and said member is adapted to operate the uppermost embossing stamps 10 without action of the underlying embossing stamps in accordance with a coin-control hereinafter to be described. Each shaft 8x, 9x and 10x is provided with a head or shoulder 14 contacted by a spring 15 mounted in a suitable recess formed within frame member 13 and the springs serve to normally project the shafts forwardly, the frame members serving as a stop for the embossing stamps per se.

To the left of the embossing stamps 8 to 10 inclusive are two additional embossing stamps carried by shafts 16x and 17x, the uppermost of the two shafts being projected forwardly a greater distance than the shaft 16x. The construction of the shafts 16x, 17x, is the same as those carrying embossing stamps 8 to 10 inclusive and each shaft held in retracted position by a corresponding spring 15.

Mounted in the casing for reciprocation is an actuating block 18 which rests upon a shelf-like support 19. The block is formed with a coarsely threaded aperture to receive a propelling screw 20, the latter having a shaft-like projection extending exteriorly of the casing and carrying operating handle 21.

Within a shallow casing 22 is a spiral spring 23 having one end fixed and the other end connected to propelling screw 20 so that the operative movement of the propelling screws is against the tension of said spring 23. By turning handle 21, actuating block 18 is moved toward the embossing stamp shafts and upon release of the handle the spring 23 will return the block to initial position. An operative movement of the block will have no effect upon the shafts, however, unless a coin or coins are in position inasmuch as the block is provided with suitable recess, as, for example, at 18x, to receive the shafts, said recesses merging into laterally projected clearances for the coins as shown in Fig. 7,

the said clearances being contiguous to coin-supporting vertical plates 24 carried by the block.

When a single coin, as, for example, a one-cent piece, is placed in slot 4, it will be guided by the 5 coin plates 24 and will descend until it rests upon shelf 19. The coin will close the block clearance for shaft 8x. When, therefore, a full operative movement is given to crank 21, block 18 will bring the coin into engagement with shaft 10 8x. A letter having been placed in the letter 15 passageway of the device, embossing stamp will be operated to emboss a one-cent postage designation upon the envelope. If a two-cent postage is required, the second one-cent piece will rest 20 upon the first and shaft 9x only will be operated because it projects toward the actuating block a greater distance than the lower shaft proportionate to the degree of operative movement of shaft 8x. If a three-cent embossing is required, the 25 two lower coin units will support the third unit in position opposite shaft 10x, the actuating block will move embossing stamp 10 to full operative position before shaft 9x is engaged by the coin opposite thereto.

25 Inasmuch as the construction of the special delivery and airmail embossing stamps and supporting shafts are the same as those previously described in detail and the uppermost of the two shafts is longer than the one underlying it, insertion of one coin will operate the lower shaft and emboss a ten-cent postage designation on the letter and the insertion of two coins will cause the uppermost one only to act, its action being upon the uppermost shaft, and embossing a 30 twenty-cent postage designation.

As hereinbefore stated, the action of the embossing stamps is through inking ribbons. At the top of the device are two opposed arms 25 each pivotally supported upon the casing as by 35 a screw stud 26 and each apertured to receive for rotation a stub shaft 27 (Fig. 4) carrying a ratchet wheel 28 and a detent wheel 29. As shown in Fig. 12, a detent spring 30 may be carried by arm 25, in each case, the spring having 40 a suitably formed head 30x for engaging the detent wheel. Stub shaft 27 is formed with a squared axial aperture to receive the squared end of spool shaft 31. Upon the shaft are two spools 32 each carrying an inking ribbon led downwardly intermediate the embossing stamps and the letter passageway 1. Each side of the actuating block pivotally supports a pawl 33 engaged by a 45 spring 34 so designed as to move the end of the pawl upwardly until the rear end of the pawl engages a stub pin 35. To each of the lower sides of the actuating blocks is fixed a carrying arm 36 for a pawl 37 engaged by spring 38 in such manner that the end of the pawl opposite the pawl head is normally held against a stop pin 39.

60 The inking ribbons at the lower end of the device are received upon two spools 40 on a spool shaft 41, Fig. 11. This spool shaft will have squared ends each to be received within the axial squared aperture of a stub shaft 42, Fig. 10, 65 which shaft is rotatably carried by arms 25x, one at each side of the casing at the lower end thereof and supported by a stud screw 26x. Each upper arm 25 is connected to the corresponding lower arm 25x by a link 43.

70 From the above construction it will be noted that each set of inking ribbon spools is on a shaft carried by swinging arms. When, therefore, the ribbons are unwound from their top spools and the lower spools continue their winding action, 75 the ribbons will come under tension and resist

further rotation of the spools. The ribbons will be firmly connected at their ends to the spools in practice.

The link 43 at each side of the device is utilized as a yielding support for the swinging arms and means are provided for quickly releasing the upper ratchet wheels from their pawl and applying the lower ratchet wheels to their pawls when the ribbons have been wound in upon the lower spools and a predetermined degree of tension is exerted upon the upper spool shaft 31. To this end, each link 43 is provided with a lateral extension 43x formed with a shallow slot 43xx to receive a pin 44x carried by a pivotally supported detent arm 44, the arm being engaged through pin 44x by a spring 45. Spaced stops 46 determine the opposite sides of the dead center of detent 44. In the position of the parts shown in Fig. 3, detent 44 is above the dead center and is so held by spring 45.

If the tension upon the ribbon *a* is such that it prevents rotation of spool shaft 41, pawl 37 in its active forward movement will bodily swing the ratchet wheel in a downwardly directed arc thus moving link 43 downwardly the slight distance 25 sufficient to bring the detent 44 to and slightly below the dead center and then spring 45 will give a quick downward movement to link 43 carrying the lower ratchet wheels 28x out of engagement with pawl 37 and carrying the upper ratchet 30 wheels 28 into engagement with their pawls 33. A reverse action is had when in the continued 35 operation of the device, the ribbons are wound fully upon the spools 32 and tension is placed upon the spools 40 and hence upon the spool 35 shaft and arms 25x, which will cause links 43 to move detent 44 upwardly past the dead center.

The operation of the coin control thumb wheel 6 is as follows:

When a single coin, as, for example, a one-cent piece is placed in slot 4 it will move downward by gravity to shelf 19 opposite shaft 8x of embossing stamp 8.

In the position of the parts shown in Fig. 11, operation of handle 21 would move the coin off the shelf and permit it to fall before contact by the coin with the end of shaft 8x. However, by moving thumb wheel 6 so that the pointer comes in register with the indication 1, the thumb wheel will turn coarsely threaded screw 47 and move shelf section 19x forwardly to increase the effective length of the shelf. Therefore, operation of the handle 21 will cause the coin to come in contact with shaft 8x and operate embossing stamp 8. When thumb wheel 6 is moved so that its pointer registers with the numeral 3 on the casing, which will move shelf extension 19x away from shelf 19 a distance sufficient to permit passage of coins downwardly from the coin chute rearwardly of plates 24 succeeding a movement of the actuating block 18 sufficient to carry the topmost of three coins, inserted through slot 4, into register with shaft 10x. Thus, the coin will be held clamped upon shaft 10x in the active movement of the actuating block, but the two lower coins will be permitted to fall downward when they come into register with a vertical line drawn intermediate shelf 19 and the shelf extension member 19x. The latter member may be provided near its lower end with a boss apertured to receive a guide post 49 secured in fixed position, the post preventing rotation of the shelf extension upon the screw 47 and thus compelling reciprocation by the screw.

When two coins are placed in coin slot 4, the 75

uppermost coin will lie in register with shaft 9x and the pointer of thumb wheel 6 may be moved in register with the casing notation 2 which will position shelf extension 19x a distance away from shelf 19 to permit passage of the coin. Thus, when handle 21 is operated to move the actuating block, the uppermost of the two coins will be clamped upon the end of shaft 9x and the bottom coin will, in the actuation of the shaft be carried to a point intermediate the shelf and the shelf extension and will drop downwardly to the coin tray A.

Means are provided for temporarily checking the return of a shaft previously actuated through a coin held by the actuating block so that in the retraction of the block the coin is released from the end of the shaft with which it has been in contact and thereafter the shaft is released. To that end, each shaft may be provided with a laterally extending stud screw 50, Fig. 9, carrying a link 51 extending parallel with the shaft but at a suitable distance laterally thereof, and frame member 13 may have secured thereto a detent spring 52, Fig. 8, adapted to enter a seat formed in the top of link 51. Thus, when the shaft is moved forwardly to its full extent in order to emboss a stamping indication upon an envelope, the detent will hold the shaft in such position. However, the end of the link is provided with a slot at 53 and a pin 54 is fixed to the actuating block 18 which will enable reciprocation of the block for a limited distance without affecting the link but continued movement will cause the pin to come in contact with an end wall of the slot 35 and forcibly move the link so that the spring detent will be released and the shaft will return to initial position. Said temporary holding of the shaft however will release the coin.

That section of shelf 19 lying under shafts 16x 40 and 17x (Fig. 10) will be higher than the section lying under shaft 8x to correspond with the respective distances of shaft 16x and 17x from the base of the device. Shelf extension 19x will in its section underlying shafts 16x and 17x have a corresponding increased height.

Although spring 45 will be generally sufficient to maintain the inking ribbon elements in each of their two positions, supplemental means may be provided, as, for example, that shown in Fig. 4. In Fig. 4, the stub shaft 27 is formed at its end with a semi-spherical recess to receive either detent 53 or 54 in accordance with the lower or upper position of the ribbon feed means. In the embodiment shown, the detents are short shafts, rounded at one end and having collars against which press coil springs 55, the assembly being enclosed within a cage 56, the shaft projecting inwardly through suitable apertures formed in casing 1. If desired, a plurality of such detent means may be employed, as, for example, one at each end of shaft 31.

It will be understood that various changes may be made in the embodiment shown without departing from the spirit of the invention, thus, any suitable means may be employed for inking the stamp members in substitution of the inking ribbon. It will also be understood that the term "embossing" is used in a broad sense to mean the application to an envelope or other mailable matter enclosure of a postage paid designation.

It will be noted that the letter box and casing may be so related as to have communication whereby opening of the letter box by the Government collection mail-man and removal of let-

ters or packages will expose coin drawer A from the interior of the letter box 1 (Fig. 11) for collection of the coins therein.

Having described my invention, what I claim and desire to secure by Letters Patent, is as follows:—

1. A postage affixing device for letters, comprising a casing having a passageway for insertion of a letter or other article to be acted upon, a supporting wall adjacent said passageway, a plurality of postage affixing members mounted forwardly of said passageway for movement, an actuating block movable toward and from said stamp members, coin passageways, coin supporting means below said passageways and adapted to support coins, each in register with a postage affixing member, means for adjusting said supporting means from a point exterior the casing, said adjusting means comprising a shaft passing through the casing, a manually operable handle exterior to the casing for rotating the shaft, and means carried by the shaft and engaging the supporting means and adapted upon rotation of the shaft to impart bodily movement to the latter toward and from the front wall of the casing, and means for moving the actuating block in reverse directions.

2. A postage affixing device for letters, comprising a casing having a passageway for insertion of an article to be acted upon, a fixed frame member within the casing, a plurality of shafts held in vertical superposed position by said frame member for endwise reciprocation, the shafts being of successively different lengths, a stamp carried at the end of each shaft, means for normally holding the stamps in retracted position in register with said passageway, an actuating block movable toward and from the shafts and having clearance for said shafts whereby movement of the block to maximum position toward said shaft does not affect the latter, coin guiding means contiguous to a wall of the actuating block and adapted to hold one coin in register with a shaft or a plurality of coins in register with successive shafts, means operable for moving the block toward and from said shafts, and coin releasing means.

3. A postage affixing device for letters comprising a casing having a passageway for insertion of a mailable article, a plurality of postage affixing members supported within the casing for endwise movement and having contact members of successively different lengths, means for moving the postage affixing members toward said passageway comprising a coin-holding carrier adapted to receive coins in succession and to support the first coin in register with one of said contact members, and a succeeding coin in register with a second of said contact members and manually operable means for moving said carrier toward the passageway, whereby one coin will engage its contact member prior to engagement by a second coin with its contact member.

4. A postage affixing device for letters constructed in accordance with claim 3 in which the contact members of successively different lengths are vertically arranged, the lowermost coin contact member being of the shortest length, whereby the uppermost of a plurality of coins placed in the coin holding carrier will, in the operation of the device, cause active movement of its appropriate contact member prior to operation of a lower contact member.

DAVID H. BROOK.
